BOOK AND METHOD OF BINDING SAME

Hyman Zaslawsy, Los Angeles, Calif., assignor
of one-half to Philip V. Spinner, Chicago, Ill.

Application November 21, 1941, Serial No. 419,942

5 Claims. (Cl. 281—21)

My invention has to do with books and methods of binding them and more particularly it relates to an improved system of book binding wherein expensive and objectionable stitching and stapling are eliminated.

Conventionally it has been the practice to sew or staple together the sections or signatures going to make up a book. This practice, however, is not only expensive but it also renders the book less compact and difficult to open flatly. I am aware that attempts have been made to bind books without the aid of sewing or stapling. For instance, I am aware that this has been attempted by first folding the sheets to form the sections and thereafter punching the folded section along the line of the fold, but this practice requires double handling of the sheets, which adds materially to the binding cost, and is otherwise unsatisfactory in that a relatively flat or sharp fold is not obtained prior to pressing, which causes air pockets and resultant wrinkling of pages, and in that an efficient glue receiving surface is not obtained and uniform folding does not take place.

It is therefore among the objects of my invention to provide a book binding in which these shortcomings of the prior art are cured; in which material savings in time and labor are achieved; in which the sections are securely mounted in the bound volume without the aid of stitching or stapling; by which is provided a book which may be flatly opened at any point; which provides a more compact, uniform and secure binding and which safeguards against wrinkling the pages during binding due to air pockets and lack of proper fold of the sheets.

How my invention is carried into practice to attain these objects as well as still further inherent advantages will be better understood from the following detailed explanation of a presently preferred adaptation thereof, for which purpose I shall refer to the accompanying drawing, in which:

Fig. 1 is a plan view of a sheet of paper bearing printed pages before being folded to provide a section;

Fig. 2 is a perspective showing the partially folded section;

Fig. 3 is an enlarged fragmentary plan view showing a perforation employed in carrying out my invention;

Fig. 4 is an enlarged fragmentary view in perspective showing a corner portion of a section formed in accordance with my invention; and

Fig. 5 is an end view showing several sections bound into a volume.

In Fig. 1, I show a sheet 5 comprised of sixteen printed pages 6 (eight pages on each side of the sheet), the area of the respective printed pages on the sheet being delineated by the rectangular frames 7. While I show a sheet containing sixteen pages, it will be understood that sheets containing a greater or lesser number of pages may be and are commonly used. The first step in carrying out my invention is to perforate the sheet along the lines to be followed by the folds, it being important to do the perforating prior to folding since it is only in this manner that the proper perforating and folding can be obtained for carrying out my invention. Therefore, I show at 10 the transverse perforations and at 12 the longitudinal perforation, the perforations preferably being sinuous and punched to present a rough edge so as to provide a more efficient and relatively greater glue receiving surface and so as to provide a plurality of rough-edged microscopic ears or tabs 10a. Preferably the perforations should be elongated as shown, leaving only relatively shorter imperforate hinge portions 11 between adjacent perforations. By this procedure it is relatively easy to obtain a very flat and sharp type of fold, with the result that the rough edges or ears 10a are superposed and projected out of the fold.

After perforating the sheet 5, it is first folded along the longitudinal perforation 12 and is next folded accordion fashion along the lines of the transverse perforations 10 into a book section as shown in Figs. 2 and 4. After the desired number of sections are thus formed, they are superposed in proper order as shown in Fig. 5, pressed together, and a suitable coating of flexible glue is applied over the exposed perforated edge and a cover 15 of suitable material such as fabric is applied over the glue-coated edge, the cover preferably extending over the top and bottom surfaces as shown at 15a in Fig. 5. The book is pressed until the glue has fully set, after which it is ready for the pages to be cut, which latter is effected by cutting the unperforated areas 11 along the front edge.

By doing the perforating prior to the folding I not only obtain a flatter, sharper and more uniform fold which more effectively exposes the rough glue-receiving edges and provides a flatter, more uniform and more securely bound book, but I also eliminate all air pockets which cause wrinkling—that is the pages, even prior to pressing, lay flatly against each other and any air

which might otherwise form pockets is forced out and allowed to escape through the perforations. Also since folding machines are equipped with perforators, the perforating and folding is all done in one handling of the sheets, which materially reduces cost.

While I have resorted to considerable detail in explaining this specific adaptation of my invention, I wish it understood that, in its broader aspects as defined by the appended claims, the invention is subject to various modifications.

I claim:

1. A book having a plurality of signatures each of which comprises a sheet having a plurality of spaced lines of perforations, each line of perforations being in the form of a series of long rough edged punctures separated by a series of substantially shorter imperforate portions, the sheet being folded along lines of perforations with certain perforations on opposite sides of a line of fold located in juxtaposition, a plurality of the folds being uniformly spaced apart and with consecutive ones of said plurality of folds extending in opposite directions, and an adhesive at said plurality of folds, said adhesive being at the perforations of the plurality of folds and securing the folded parts of the signature sheet together and to the adjacent signatures.

2. The method of making a book which comprises providing a single sheet that is to be folded to constitute a plurality of pages, perforating the unfolded sheet along the lines along which it is to be folded, each line of perforations being made in the form of a series of long rough edged punctures separated by a series of shorter imperforate portions, forming the sheet into a signature by folding the sheet in a series of successive folds that bring spaced lines of perforations into juxtaposed position whereby an edge of the signature comprises a series of folds along lines of perforations, stacking a plurality of such signatures one upon the other, and adhering the stack of signatures together by applying an adhesive to the rough edges at one surface of the stack.

3. The method of making a book which comprises providing a single sheet that is to be folded to constitute a plurality of pages, perforating the unfolded sheet along the lines along which it is to be folded, each line of perforations being made in the form of a series of long rough edged punc-

tures separated by a series of shorter imperforate portions, forming the sheet into a signature by folding the sheet in a series of successive folds that bring spaced lines of perforations into juxtaposed position with consecutive folds of the series being made in opposite directions whereby an edge of the signature comprises a series of folds along lines of perforations, stacking a plurality of such signatures one upon the other, and adhering the stack of signatures together by applying an adhesive to the rough edges at one surface of the stack.

4. The method of making a book which comprises providing a single sheet that is to be folded to constitute a plurality of pages, perforating the sheet along each of the lines along which it is to be folded, each line of perforations being made in the form of a series of long rough edged punctures separated by a series of shorter imperforate portions, forming the sheet into a signature by folding the sheet by a series of parallel uniformly spaced folds and with consecutive folds of the series being in opposite directions whereby an edge of the signature comprises a series of superimposed folds, stacking a plurality of such signatures one upon the other, and adhering the stack of signatures together by applying an adhesive to the rough edges at one surface of the stack.

5. The method of making a book which comprises providing a single sheet that is to be folded to constitute a plurality of pages, perforating the sheet along each of the lines along which it is to be folded, each line of perforations being made in the form of a series of long rough edged punctures separated by a series of shorter imperforate portions, forming the sheet into a signature by folding the sheet once along a line of fold extending lengthwise thereof to form a double sheet, then folding the sheet by a series of parallel uniformly spaced folds at right angles to the first fold and with consecutive folds of the series being in opposite directions whereby an edge of the signature comprises a series of superimposed folds of only a double sheet, stacking a plurality of such signatures one upon the other, and adhering the stack of signatures together by applying an adhesive to the rough edges at one surface of the stack.

HYMAN ZASLAWSKY.
